H. Lee Stevens

UNITED STATES PATENT OFFICE.

MAX BEILOCK, OF NEW YORK, N. Y.

MASTOID BANDAGE.

Application filed November 6, 1922. Serial No. 599,228.

To all whom it may concern:

Be it known that I, MAX BEILOCK, a citizen of the United States, residing in New York, county and State of New York, have 5 invented certain new and useful Improvements in Mastoid Bandages, of which the following is a specification.

My invention relates to a bandage adapted for use upon the human head following an 10 operation for mastoiditis. In the past, following such an operation it has been the practice to cover the wound with a packing of sterilized absorbent cotton and to hold the same in position and thoroughly shield 15 the wound against the air, by means of windings of linen or cotton strips crossing the packing and wound about the head of the patient and finally held by stitching or adhesive tape. Such, generally, is the universal practice at the present time.

The wound must be dressed daily for many days following the operation and this requires unwinding the cloth strips to expose the packing and the removal of the latter with the substitution of a fresh packing. Usually the drainage from the wound has penetrated the packing and several windings of the cloth strips so that each dressing requires, in addition to a fresh 30 packing, a new set of the cloth strips. It is the object of the present invention to provide a bandage which will obviate the necessity of employing the usual cloth strips and which will even more effectively protect the wound, while at the same time greatly reducing the time required to bandage the wound. Further objects are to render the dressing more slightly in appearance and permitting the patient to wear a 35 hat of his usual size—which was an impossibility heretofore because of the bulk of the windings about the head.

The invention will be understood by reference to the accompanying drawings, in 40 which—

Fig. 1 is a side elevation showing the bandage upon the head of a patient, and

Fig. 2 is a perspective view of the bandage.

Fig. 3 is a fragmentary sectional view through the edge of the bandage to illustrate the construction thereof.

By reference to the drawing it will be seen that the bandage consists of a cupped 55 shield A adapted to cover the ear and the mastoid. It is cupped so as to receive a

packing which I prefer to form of absorbent cotton sterilized by heat and enclosed within a sterilized fabric coarsely woven of fine strands, similar to cheesecloth. These packings may be made up in advance so as to be ready for each dressing operation.

The entire edge of the bandage carries a relatively soft metallic wire 1. In the present embodiment the outer member or cover of the bandage at its edge is turned inwardly and over the wire so as to enclose the same, stitching 2 being employed to hold the wire in the pocket thus formed. The entire inner surface of the bandage is formed of imper- 60 65 70 75 80 85

vious, moistureproof material such as rubber. I prefer to employ the construction illustrated in Fig. 3, in which the inner surface of the bandage comprises a rubber lining 3, held in position by the stitching 2 and having its margin projecting beyond the edge of the wired edge of the outer member.

The inner surface of the bandage may be an integral part of the outer member. For example, a single ply of heavy fabric may be employed, with the inner face impregnated and coated with rubber subsequently vulcanized to afford a lasting moistureproof surface. Or the entire body of the bandage 85 may be formed of rubber.

The bandage is held in position upon the head by means of straps, which in the present instance consist of a transverse strap 4 which passes over the head centrally thereof, a strap 5 which leads from the lower margin of the bandage, thence to the side of the head opposite to that at which the bandage is placed, crossing the temple and being secured to the top of the bandage at its front margin. A short connecting strap 6 connects the top of the bandage at its rear margin with strap 5. However the bandage is adapted for use upon either right or left mastoid. By reversing its position from that shown in Fig. 1 the bandage may be applied to the left mastoid.

As hereinbefore stated it is deemed essential to cover the packing with a substantially air-proof covering. I am able to seal the edges of my bandage upon the head by means of the conforming marginal area thereof in conjunction with the action of the straps. The soft wire, in practice, may be bent to shape the marginal area of the bandage in strict conformity with the contour of the patient's head, and the drawing action of

the straps—which should be of elastic webbing or rubber—will press the rubber inner surface of the bandage into close contact with the head.

- 5 Any suitable adjustments for the straps may be provided. I have indicated one adjustment by means of the buckle 7 which will serve to permit variations in the length of strap 5. A similar adjustment may be 10 provided for strap 4. In practice, however, it will be found desirable to eliminate all metal parts from the bandage, and to rely upon the elasticity of the straps and variations in sizes for adults and children, men 15 and women, with the exception of the marginal wire which may consist of a non-corrosive alloy of silver and zinc or any other suitable metal or combination of metals affording the desired characteristics.

20 It will be understood that various modi-

fications may be made in the embodiment of the invention illustrated in the drawings without departing from the spirit of the invention, what I claim and desire to secure by Letters Patent being as follows:

25 A mastoid bandage comprising a cupped shield said shield comprising an outer member of woven fabric and an inner member of rubber, a soft wire enclosed within the margin of the shield intermediate its two 30 members, the inner rubber member projecting outwardly beyond said wire, and means for securing the bandage upon the head.

In testimony whereof, I have signed my name to this specification in the presence of 35 two subscribing witnesses.

MAX BEILOCK.
